Fig. 9

Fig. 8

FIGURE 1 is a side elevational view of a combined escutcheon, indicator light means, and base for an electric switch or similar article, showing our new design; FIG. 2 is a right-end elevational view thereof; FIG. 3 is a left-end elevational view thereof; FIG. 4 is a top plan view thereof;

FIG. 5 is a partial sectional view taken on the line 5-5 of FIG. 4; FIG. 6 is an isometric view thereof;

FIG. 7 is an isometric view of the combined escutcheon, indicator light means, and base for an electric switch or similar article shown in FIG. 6 but showing a modified embodiment thereof;

FIG. 8 is a side elevational view thereof; and FIG. 9 is a top plan view thereof.

The dominant features of our new design are shown in full lines. The broken-line showing of the base portion is fragmentarily depicted in FIGS. 6 and 7 for convenience of illustration.

The broken-line showing of a mounting plate in FIGS. 1, 2, 3 and 8 is for illustration purposes only, as is the showing of pushbuttons in FIGS. 1, 2, 3, 4, 8 and 9.

We claim:

The ornamental design for a combined escutcheon, indicator light means, and base for an electric switch or similar article, substantially as shown and described.
